UNITED STATES PATENT OFFICE.

CECIL H. BOYULS, OF LOUISVILLE, KENTUCKY.

METHOD OF IRONING GARMENTS.

Application filed December 1, 1921. Serial No. 519,123.

To all whom it may concern:

Be it known that CECIL H. BOYULS, a citizen of the United States of America, residing at Louisville, in the county of Jefferson 5 and State of Kentucky, has invented certain new and useful Improvements in Methods of Ironing Garments, of which the following is a specification.

This invention relates to the art of ironing garments and has special reference to a method of ironing open front garments such as shirts and the like.

Heretofore in the machine ironing of shirts it has always been found essential in 10 open front shirts and other like open front garments to hold either the entire open edges in overlapping position or at least a portion of such edges in such overlapped position. In the case of open front shirts this has usually been done by the insertion of a collar 15 button in the front buttonholes of the neckband of such shirt. In the methods previously employed it has been customary to place a shirt in this condition on a buck or 20 board and then bring into contact with the bosom of the shirt a hot pressing iron. This method is objectionable inasmuch as 25 the portions of the shirt which overlap are not properly pressed by the iron, the upper 30 surface of the underlying portion and under surface of the overlying portion being unaffected or insufficiently affected by the action of the iron. This has been sought to 35 be overcome by the insertion of a metallic pressing strip between these portions of the shirt but this produces into the ironing of 40 the shirt an additional operation which, on account of the care required in adjusting this strip, greatly retards the speed of the operation. Another method which has been used 45 in an endeavor to overcome this serious defect is to button the collarband and then arrange the tail portions of the shirt in diverging relation, these tail portions being held by clamps in that position. This 50 partly overcomes the difficulty since it allows for the lower parts of the edge portions of the opening to be pressed by the iron. However, the portion of the shirt adjacent the neckband still remains improperly 55 pressed and as a natural consequence it is necessary to subject these portions of the shirt to an operation with an ordinary hand iron after taking the garment off of the board.

One important object of the present invention is to so improve the method of ironing shirt bosoms in open front shirts that there will be no need of auxiliary pressing strips or of any operation by a hand iron, the 60 bosom being completely and satisfactorily ironed in every respect by the action of the ironing member.

Furthermore in the methods heretofore employed the bosom only of the shirt is 65 ironed in this operation while the major portion of the shirt has to be subjected to a second ironing operation of one sort or another.

A second important object of the invention is the provision of a method whereby the entire body of the shirt may be properly and effectively treated so that when removed from the form all parts of the body will be left in the required smooth shape just as 75 effectively as though the entire body had been hand ironed with great care.

In addition to this it is well known that a slipping or sliding of the iron over the surface to be ironed aids greatly in accomplishing the required result especially in the 80 treatment of shirt bosoms.

Another important object of the invention is to so apply hot pressure to a shirt bosom that the pressing tool, while effectively exerting a very heavy pressure, will at the same time slip slightly over the surface, the slipping being accomplished in a manner which is practically simultaneous with the exertion of the greatest pressure 90 on the shirt.

With the above and other objects in view, as will be hereinafter apparent, the invention consists in an improved method for treating a garment of the general type of 95 an open front shirt in such manner as to effectively smooth the entire body of the garment in a single operation.

The accompanying drawings disclose a general diagrammatic type of machine 100 adapted for this purpose together with views showing the different steps in the method as preferably carried out, like characters of reference indicating like parts in these various views.

Figure 1 is a front elevation of a garment pressing machine for the purpose of carrying this method into operation, the machine being merely typical and the elevation being somewhat diagrammatic in character.

Figure 2 is a side elevation of such a machine, the view being of the same character as Figure 1.

Figure 3 is a view of the same character as Figures 1 and 2 and disclosing the plan of the machine.

Figure 4 is a view typifying a cross section through the expanding former.

Figure 5 is a diagrammatic view showing 10 a shirt as arranged generally on the former in the first step of the method.

Figure 6 is a similar view showing the second step of the method.

Figure 7 is a diagrammatic view showing 15 a garment in its final position in which it remains till completely finished.

In carrying out the invention a machine is used which consists in general of a base 10 having a standard 11 projecting up 20 therefrom and extending rearwardly and upwardly from the standard is an expandible form consisting of a center hollow body portion 12 and wings 13 adjustable to and from the body portions in any suitable 25 manner, as for instance by means of a shaft 14 having an operating crank 15 thereon, the shaft carrying a gear 16 which meshes with racks 17 attached to the wings 13. Suitable steam and exhaust piping 18 is connected to these parts in such a way that they 30 may be properly heated, the exact arrangement not being of importance in carrying out the method. Suitably pivoted adjacent the board is shown an iron 19 which is ar- 35 ranged to swing in a vertical plane and which has its under side beveled as shown in Figure 2 so as to make contact with the slanting face of the expansible form. This iron may be supplied with steam and the 40 steam may be exhausted therefrom through pipes such as are shown at 20. It is to be understood at this time that the machine just described is simply a type machine re- 45 sembling in its general construction ma- chines which are at present employed for the purposes of garment ironing and that it is not desired to enter into the details of the construction further than to disclose such de- 50 tails as may be necessary to effectively ac- complish the method now to be disclosed.

Also this board is provided with a collar band holder which consists of a stationary member 21 having an arcuate and inclined front and a clamp member 22 movable to 55 surround or to leave clear this arcuate front, the clamp being actuated by suitable han- 60 dle 23. Turning now to the particular method which forms the subject matter of this invention it is to be understood that 65 this method is applicable to any garment having a body which is slit from top to bottom and an open front shirt has been used as typical of this general form of garment. Accordingly it is to be understood that 70 wherever in the specification and claims the

term "open front shirt" is used this term is to be understood broadly as including all garments of this general type.

In the first step of the operation the iron 19 is in a raised position clear of the board 70 and the neckband clamp is open. The operator takes the shirt and adjusts it over the board or form with the neck portion in such position that the edges are close together but do not overlap. The neckband clamp is now 75 closed so that the upper portion of the garment is held in this position. The operator then seizes the tail portions of the garment and draws them down in such position that no part of the proximal edges of the garment overlap. The iron is then swung down onto the board as shown in Figure 6 and sufficient pressure is applied to the iron to cause it to effectively perform its work. Since the iron moves in a perpendicular 80 plane and its lower face and the board are inclined the contact of the iron with the board or form is in a line at an angle there- 85 to so that when this pressure is applied the natural yielding of the parts to a slight de- 90 gree permits a slight longitudinal move- ment of the iron along the board. This movement is, of course, very slight but inasmuch as the pressure of the iron is heavy this slight movement fully accomplishes the 95 purpose. Now while the iron is in this po- 100 sition the operator expands the form so that the body of the shirt is thoroughly dis- tended. Since either the iron, the board, or both may be heated the pressure exerted 105 is a hot pressure. Since the garment is thoroughly distended all wrinkles and creases will be drawn out of the damp gar- 110 ment and by leaving the garment on the ex- panded form until it is thoroughly dry the 115 finished garment will be smooth and un- wrinkled in the same manner as though it had been ironed with an ordinary hand iron. Moreover it will be noted that the pressure of the iron on the board is sufficient to cause 120 the edge portions of the opening in the shirt from slipping to any material extent. By this method experience has shown that the shirt when removed is completely and fully finished in regard to the body portion and that all use of a hand iron on this body portion is rendered unnecessary, every part of the shirt body being completely and properly finished.

There has thus been provided a simple and 125 improved method of the kind described and for the purpose specified.

Having thus described the method and a type of apparatus for carrying the same into execution what is claimed as new, is:

1. That method of ironing a garment hav- 130 ing an opening from top to bottom through the material of said garment, which con- sists in placing the garment upon a form with the edges of the opening in non-over-

- lapping arrangement, applying pressure and heat to a portion of the garment adjacent said edges, and stretching the garment laterally away from the point of application 5 of the pressure and heat.
2. That method of ironing an open front shirt or the like, which consists in arranging the shirt on a form with its front edges in juxtaposition but with non-overlapping 10 relations throughout their length, applying pressure and heat to the shirt front adjacent its front edges, and stretching the garment laterally away from the point of application of the pressure and heat.
- 15 3. That method of ironing an open front shirt or the like, which consists in arranging the shirt on a form with its front edges in juxtaposition but in non-overlapping relation throughout their length, clamping 20 the garment to a form, and simultaneously heating the clamped portion, and stretching the garment laterally away from said clamped portion.
4. That method of ironing an open front 25 shirt or the like, which consists in arranging the shirt on a form with its front edges in juxtaposition but in non-overlapping relations throughout their length, clamping the front edges of the shirt to the form by a 30 pressure sufficient to hold said edges against any material lateral movement, simultaneously heating the clamped portion, and stretching the portions of the garment adjacent the clamp laterally.
- 35 5. That method of ironing an open front shirt or the like, which consists in arranging the shirt on a form with its front edges in parallel spaced relation throughout their length, applying pressure and heat to the 40 bosom portion of said shirt, the pressure being sufficient to hold the shirt on the form

against lateral slipping and stretching the shirt laterally adjacent the pressed portion.

6. That method of ironing an open front shirt or the like which consists in arranging the shirt on a form with its upper edges in juxtaposition but in non-overlapping relation throughout their length, and applying pressure and heat to the portion of the shirt adjacent said front edges by means of 45 a pressing member movable into engagement with the form at an angle thereto whereby to produce sliding pressure on the shirt front.

7. That method of ironing an open front 55 shirt or the like, which consists in arranging the shirt on a form with its front edges in juxtaposition but in non-overlapping relation throughout their length, applying heat and pressure to the portion of the shirt 60 adjacent the front edges by means of a pressing member movable into engagement with the form on an angle thereto whereby to produce sliding pressure on the shirt front, and stretching the portions of the 65 shirt adjacent the pressing member.

8. That method of ironing an open front shirt or the like, which consists in arranging the shirt on a form with its front edges in juxtaposition but in non-overlapping relation 70 throughout their length, applying heat and pressure to the portion of the shirt adjacent the front edges by means of a pressing member movable into engagement with the form at an angle thereto whereby 75 to produce sliding pressure on the shirt front, stretching the portions of the shirt adjacent the pressing member, by stress exerted laterally away from said pressing member.

In testimony whereof I affix my signature.
CECIL H. BOYULS.
